EDWARD D. PRITCHARD, OF NEW YORK, N. Y.

Letters Patent No. 91,769, dated June 22, 1869.

IMPROVEMENT IN LOW-WATER INDICATORS.

The Schedule referred to in these Letters Patent and making part of the same.

To all whom it may concern:

Be it known that I, EDWARD D. PRITCHARD, of the city, county, and State of New York, have invented a new and improved Gauge and Alarm for Steam-Boilers; and I do hereby declare the following to be a full, clear, and exact description thereof, which will enable those skilled in the art to make and use the same, reference being had to the accompanying drawing, forming part of this specification, in which drawing—

Figure 1 represents a vertical central section of this invention.

Figure 2 is a horizontal section of the same.

Similar letters indicate corresponding parts.

This invention relates to a gauge and alarm which is so constructed that an alarm will be sounded whenever the water in the steam-generator gets low, or whenever the water in the gauge-tube is allowed to waste while steam is up.

The invention consists in the arrangement of a perforated plunger in the bottom end of the gauge-tube, in combination with a valve in the top end thereof, and below the alarm-whistle, and with a ball, which, whenever the water in the gauge-tube sinks down below the plunger, serves as a valve, closing up the perforation in said plunger in such a manner, that whenever the water in the boiler gets low, the valve leading to the whistle will be opened automatically by the action of the steam on the plunger, and the alarm will be sounded.

The stop-cock which controls the water-connection with the boiler, is so constructed that whenever the water-connection is closed, the water-pipe of the gauge is opened, the gauge-tube is emptied, and the alarm is sounded, and thereby the engineer or fireman is prevented from shutting off the water-connection of the gauge without being detected.

The stem or spindle which supports the alarm-whistle is made tubular, and provided with a plunger, which connects with an indicator in the office of the building in which the steam-boiler is placed, in such a manner that whenever a current of steam passes through the whistle, the indicator is moved, and caused to exhibit the fact that the alarm sounds.

With the gauge-tube is combined a steam-gauge, which takes its steam from the interior of said gauge-tube, so that whenever the steam-connection between the gauge-tube and the boiler is shut off, the steam-gauge will point to zero, and the fact that the alarm-gauge has been tampered with will be apparent at a glance.

In the drawing, the letter A designates a gauge-tube, made of glass or any other transparent material, and fastened, at its ends, in the brackets B B', the joints being made steam and water-tight by India-rubber or other suitable packing.

The lower bracket, B, is bored out, to receive the plunger a, and it is provided with a channel, b, which leads to the interior of the boiler, and is situated on a level with or below the low-water line of the boiler.

Said channel is fitted with a stop-cock, c, which is operated by a screw-thread, d, and which is provided with two channels, e f, one extending transversely through it, and the other being angular, extending from the inner end of the plug of the stop-cock, and out through one side thereof, as shown in the drawing.

The plunger a is also provided with a central channel, g, which is in line with the waste-channel h, in the bottom part of the bracket B.

If the stop-cock is so adjusted that the side-opening of the channel f is in line with the channel g in the plunger, the gauge-tube is in communication with the water-space of the boiler; but if the stop-cock is turned in, so as to shut off the water-connection of the gauge-tube, the channel e comes in line with the channel g of the plunger a, and with the waste-channel h of the bracket, and the water in the gauge-tube runs out.

The bracket B' is bored out, and provided with a pipe, i, which forms the steam-connection of the gauge-tube, and a stop-cock, k, secured in said pipe i, serves to open or close the steam-connection of the gauge-tube at will.

In the upper part of the bracket B', above the steam-connection pipe i, is a seat, l, fitted with a valve, m, which is drawn up by a spring, n.

C is a steam-gauge, which connects with the bracket B', below its valve m, by means of a pipe, o. This steam-gauge may be situated either in the engine-room, or in the office of the building or factory in which the steam-boiler is located.

The valve m connects, by rods p, with the plunger a in the lower bracket, and the area of the plunger is somewhat larger than that of the valve, so that if steam is admitted to the gauge-tube while the lower or outer surface of the plunger is relieved from pressure, the valve will be opened automatically by the action of the steam on the plunger a, and the steam will escape through the opening, q, in the top of the bracket B'. This opening is surmounted by a steam-whistle, D, the stem or spindle r of which is hollow, and closed on its top by a valve, s, which is depressed on its seat by a spring, t.

From this valve extends a rod, u, which is intended to connect with a suitable indicator in the office.

The lower part of the spindle r is perforated, to allow the steam admitted through the valve m to pass into the whistle D, and to sound the alarm.

The rods p also serve as guides for a spherical float, v, which indicates the level of the water in the gauge-tube, and which, when permitted to sink down, acts as a valve, closing the channel g in the plunger a.

The gauge-tube A is surrounded by a jacket, E, of

sheet-metal or other suitable material, and said jacket is provided with one or more windows, *w*, through which the level of the water in the gauge-tube can be observed.

The operation is as follows:

If the steam and water-connections of the gauge-tube are opened, the water in said gauge-tube will rise to a level with the water in the boiler, the float *v* being buoyed up, as shown in full outlines in fig. 1.

If the water in the boiler sinks below the plunger *a*, the valve *m* is opened by the pressure of the steam on said plunger, and the alarm is sounded.

If the engineer or fireman, in order to conceal his negligence, should turn off the steam-connection and the water-connection, the steam-gauge will recede to zero, and show the negligence. Or if he should turn off the water-connection, he will, at the same instant, open the waste-channel *h*, the gauge-tube empties, and the alarm is sounded.

The steam rushing up through the hollow spindle of the whistle, also acts on the valve *s*, and by raising said valve, actuates the indicator, and thereby the at-

tention of parties in the office is called to the fact that something is wrong with the steam-boiler.

Having thus described my invention,

What I claim as new, and desire to secure by Letters Patent, is—

1. The plunger *a* and valve *m*, connected together by rods *p*, in combination with the spherical float *v* and gauge-tube *A*, substantially as shown and described.

2. The stop-cock *c*, provided with channels *e f*, as described, in combination with the plunger *a*, float *v*, valve *m*, and gauge-tube *A*, substantially as set forth.

3. The combination of the steam-gauge *C* to the upper part of the gauge-tube, or the upper bracket *B*, as described.

4. The valve *s*, in combination with the tubular spindle of the steam-whistle *D*, and with a rod, *u*, substantially as set forth.

EDWARD D. PRITCHARD.
